UNITED STATES PATENT OFFICE.

HERMAN K. ANSINGH, OF TORONTO, CANADA, ASSIGNOR TO WESTINGHOUSE ELECTRIC & MANUFACTURING COMPANY, A CORPORATION OF PENNSYLVANIA.

SWITCH MECHANISM.

Application filed February 20, 1923. Serial No. 620,150.

To all whom it may concern:

Be it known that I, HERMAN K. ANSINGH, a citizen of the United States, and a resident of Toronto, Canada, have invented a new and useful Improvement in Switch Mechanism, of which the following is a specification.

My invention relates to switch mechanism and particularly to current-distributing panels used for controlling the control circuits of the truck-type circuit breakers.

One object of my invention is to provide a distributing panel that may be built up from standard parts to constitute a panel having any desired number of circuits and which may readily be altered, as circumstances demand, for any desired number of circuit breakers.

It will be understood that, where a plurality of truck-type circuit breakers are arranged in a row, the feed conductors for the control circuits extend through the circuit-breaker cells from one to another and the feed conductors are connected to various circuits in each individual cell.

Another object of my invention is to provide a distributing panel, having the above characteristics, wherein the insulating base for supporting the various conductors is adjustably mounted within the cell in an inclined position and is provided with distributing bars adapted to be slidably engaged by contacts carried by the truck when the truck carrying the circuit breaker is moved into the enclosing cell.

Another object of my invention is to provide a distributing panel with parallel feed conductors and with intersecting distributing bars that may be selectively connected in such manner that any distributing bar may be connected to any preferred feed conductor.

Another object of my invention is to provide a distributing panel having distributing bars adapted for engagement by a yielding contact member on the truck, the bars being so arranged that an extensive surface is exposed over which the yielding contact slides when the truck is moved to closed position, thereby rendering the distributing bars and contacts self-cleaning.

These and other objects, that will be made apparent throughout the further description of my invention, are attained by means of the apparatus hereinafter described and

illustrated in the accompanying drawing, wherein

Figure 1 is a transverse section through a portion of a truck-type circuit-breaker cell, showing the distributing panel in plan view, and

Fig. 2 is a transverse section through the panel mechanism shown in Fig. 1, taken on the line II—II of Fig. 1.

The distributing panel illustrated in the drawing is similar to the distributing panel shown in the truck-type circuit breaker disclosed in my co-pending application Serial No. 620,149, filed Feb. 20, 1923, and it comprises an insulating base member 3 that is detachably secured to the upper portion of the enclosing cell 4 by means of a bar 5 that is attached to the base member by means of bolts 6. Clips 7 are secured to the frame 8 of the cell 4 and are provided with slots 9 for receiving the projecting ends 11 of the bar 5.

The free end of the base member 3 is detachably secured to the cell 4 by means of an angle iron 12 that is detachably secured to the upper wall of the cell 4, and a bar 13 that is slidably attached to the bolts 14 which are threaded into the bar 12. The free end of the base member 3 is provided with an inclined corner surface 15 for engaging the bar 13. When the bolts 14 are screwed into the bar 12, the base member 3 is securely held in fixed position in the cell.

The angle iron 12 is made adjustable so that it may be placed at different positions upon the cell wall for accommodating base members of different lengths. By reason of the pivoted connection of the panel at one end, base members of different lengths may readily be clamped to the cell wall.

As illustrated in the drawings, the panel is provided with nine feed conductors 16 that are connected to corresponding feed bars 17 that are secured upon the insulating base 3 by screws 18. On the other side of the base members, as many distributing bars 19 as may be desired are secured by screws 21 that extend through the base members and are threaded into the bars, as indicated in Fig. 2. The bars 19 intersect the bars 17 and are adapted to be selectively connected by means of screws 22.

As indicated in the drawings, each distributing bar is connected to a different

feed bar. In case it is desirable to change the connections of the bars, they may be provided with suitable holes 23 placed at the points of intersection of the bars for receiving the connecting screws 22.

As indicated in Fig. 2, the base member 3 is mounted in an inclined position with respect to the horizontal track (not shown) upon which the truck operates. In Fig. 2,

10 a portion of the truck frame 24 is shown upon which is mounted an insulating block 25 having a longitudinally movable contact pin 26 that is slidably mounted in a metal guide member 27 with which an insulating block 25 is provided. The pin 26 is provided with a flange 28 for limiting its outward movement which is normally effected by a helical spring 29 mounted within a socket 31 in the insulating base 25. The guide member 27 is secured to the panel by means of bolts 32 and 33, the latter of which serves as a terminal for the control conductors 34 that lead to the circuit-breaker control mechanism.

15 As shown, the truck frame 24 is in its closed position wherein the pin 26 is in yielding engagement with the surface of the distributing bar 19. As the truck is withdrawn from the cell, the contact pin 26 wipes over the surface of the distributing bar 19, cleaning it as the truck is withdrawn.

20 When the panel is moved into the cell, the pin 26 engages the inclined distributing bar 19 shortly after it passes the outer end thereof and wipes the surface of the distributing bar and the pin throughout the remainder of the closing movement, the pin, at the time, being yieldingly pressed against the contact surface of the distributing bar by the spring 29.

25 In order to provide for a greater number of feed conductors, the length of the insulating base 3 is increased, which necessitates readjustment of the clamping bars 13 upon the cell. The length of the distributing bars is correspondingly increased. It is apparent that the construction renders the device flexible and capable of being altered, with minimum of expense, to accommodate 30 any desired number of control circuits and feed conductors.

35 While I have described and illustrated but one embodiment of my invention, it will be apparent to those skilled in the art that various changes, modifications, substitutions, additions and omissions may be made therein without departing from the spirit and scope of my invention, as set forth in the appended claims.

40 I claim as my invention:

45 1. A distributing panel for truck-panel circuit breakers comprising an insulating base having parallel feed conductors on one side and parallel distributing bars on the other side of the base intersecting the feed

conductors and adapted for engagement with a contact member and means for selectively connecting the distributing bars to the feed conductors.

50 2. A distributing panel for truck-panel circuit breakers having a truck for the circuit breaker and an enclosing cell for the truck, comprising an insulating base member mounted on the cell, parallel feed conductors on the base member, parallel distributing bars on the base member and intersecting the feed conductors, means for connecting the distributing bars to the feed conductors and contact members carried on the truck for engaging the said distributing bars when the truck is moved into the cell.

55 3. A distributing panel for truck-panel circuit breakers having a truck for the circuit breaker and an enclosing cell for the truck, comprising an insulating base member mounted on the cell, parallel feed conductors on the base member, parallel distributing bars on the base member intersecting the feed conductors and disposed in the direction of movement of the truck, means for connecting the said conductors and bars and yielding contact members on the truck for slidably engaging the distributing bars as the truck is moved into the cell.

60 4. A distributing panel for truck-panel circuit breakers having a truck for the circuit breaker and an enclosing cell for the truck, comprising an insulating base member adjustably mounted on the cell, parallel feed conductors on the base member, parallel distributing bars on the base member intersecting the feed conductors and arranged in the direction of movement of the truck, means for connecting the said conductors and bars and yielding contact members on the truck for slidably engaging the distributing bars as the truck is moved into the cell.

65 5. A distributing panel for truck-panel circuit breakers having a truck for the circuit breaker and an enclosing cell for the truck comprising an insulating base member mounted in an inclined position on the cell, parallel feed conductors on the base member, parallel distributing bars on the base member intersecting the feed conductors and arranged in the direction of movement of the truck, means for connecting the said conductors and bars and yielding contact members on the truck for slidably engaging the distributing bars as the truck is moved into the cell.

70 6. A distributing panel for a truck-panel circuit breaker having a truck for the circuit breaker and an enclosing cell for the truck, comprising an insulating base member having distributing bars thereon adapted to be engaged by the truck when the truck is moved into the cell, detachable

means for pivotally securing the base member to the cell and adjustable means for supporting the free end of the base member.

7. A distributing panel for a truck-panel circuit breaker having a truck for the circuit breaker and an enclosing cell for the truck, comprising an insulating base member having distributing bars thereon adapted to be engaged by the truck when the truck is moved into the cell, means for pivotally securing the base member to the cell and adjustable means for supporting the free end of the base member in an inclined position.
8. A distributing panel for truck-panel circuit breakers comprising an insulating base having a plurality of feed conductors on one side and a plurality of distributing bars on the other side of the base intersecting the feed conductors and adapted for en-

gagement with a contact member, and means for selectively connecting the distributing bars to the feed conductors.

9. A distributing panel for truck-panel circuit breakers having a truck for the circuit breaker and an enclosing cell for the truck, comprising an insulating base member mounted on the cell, a plurality of feed conductors on the base member, a plurality of distributing bars on the base member and intersecting the feed conductors, means for connecting the distributing bars to the feed conductors and contact members carried on the truck for engaging the said distributing bars when the truck is moved into the cell.

In testimony whereof, I have hereunto subscribed my name this ninth day of February 1923.

HERMAN K. ANSINGH.
